Primary Examiner — Ania Aman(74) *Attorney, Agent, or Firm* — Lerner, David, Littenberg, Krumholz & Mentlik, LLP(57) **CLAIM**

The ornamental design for an automobile breather cap, as shown and described.

DESCRIPTION

FIG. 1 is a front perspective view of an automobile breather cap according to my design;

FIG. 2 is a front elevation view thereof, the rear elevation view being identical thereto;

FIG. 3 is a right side elevation view thereof, the left side elevation view being identical thereto;

FIG. 4 is a top plan view thereof; and,

FIG. 5 is a bottom plan view thereof.

The broken lines shown in the drawings are for the purpose of illustrating environmental structure and form no part of the claimed design. The dot-dash lines are boundary lines and form no part of the claimed design.
